United States Patent Office

Des. 229,685
Patented Dec. 25, 1973

229,685

HOUSING MODULE

Mark L. Hildebrand, Altadena, Calif.
(157 Bowers Hill Road, Oxford, Conn. 06483)

Filed Sept. 1, 1971, Ser. No. 177,207

Term of patent 14 years

Int. Cl. D25—02

U.S. Cl. D13—1 R

FIGS. 1 and 2 are perspective views of the elements as shown in FIG. 10.

FIGS. 3, 4 and 5 are, respectively, the top, back and side views of the elements of FIG. 2.

FIG. 6 is a cross-sectional view through 6-6 of FIG. 4.

FIGS. 7, 8 and 9 are, respectively, cross-sectional views through 7-7, 8-8 and 9-9 of FIG. 6.

FIG. 10 is a perspective view of my housing module.

FIG. 11 is another perspective view of the housing module of FIG. 10 in which one end is closed by a wall containing a door.

FIG. 12 is another perspective view of the housing module of FIGS. 10 and 11 in which two sides have been shown open to illustrate the interior design of the elements.

I claim:

The ornamental design for a housing module, substantially as shown and described.
